Fig. 1

Fig. 2

Fig. 3

Fig. 4

Figure 1 is a perspective view of a combined copying camera and film and print finishing cabinet or similar article showing our new design, the opposite side being substantially a mirror image of the side shown, except for the control panel;

Figure 2 is a top plan view thereof;

Figure 3 is a vertical section thereof, viewed along the line 3-3 of Figure 2; and

Figure 4 is a rear elevational view thereof.

The dominant features of our design reside in the full line portions of the drawing.

We claim:

The ornamental design for a combined copying camera and film and print finishing cabinet or similar article, as shown and described.
